(57) **CLAIM**

The ornamental design for an electric pool cleaner, as shown and described.

DESCRIPTION

FIG. 1 is a front view of an electric pool cleaner of the present design;

FIG. 2 is a back view of the electric pool cleaner of the present design;

FIG. 3 is a left view of the electric pool cleaner of the present design;

FIG. 4 is a right side view of the electric pool cleaner of the present design;

FIG. 5 is a bottom view of the electric pool cleaner of the present design;

FIG. 6 is a top view of the electric pool cleaner of the present design; and,

FIG. 7 is a perspective view of the electric pool cleaner of the present design.

The dashed lines depict portions of the electric pool cleaner that form no part of the claimed design.
